UNITED STATES PATENT OFFICE.

ERNST MÜLLER, OF BERN, SWITZERLAND.

MACHINE FOR CASTING STEREOPLATE HAVING A MOLD ADAPTED TO BE
PRESSED AGAINST THE OUTLET OPENING OF THE POT.

Application filed March 1, 1927, Serial No. 171,837, and in Germany March 1, 1926.

My invention relates to improvements in driving devices for automatic casting machines for stereo-plates of the type in which the casting box and metal pot, in the casting 5 operation, are in such continuous communication that the contents of the pot replace the riser or head which otherwise has to be cast with the plate. According to my invention a continuously rotating shaft 10 drives a timing shaft—through the agency of which the organ controlling the flow of metal out of the pot, such as a rotary valve, and the casting box itself, are periodically operated—in the moving periods of the controlling organ and box, quickly, and, in the 15 periods of rest, slowly.

By this arrangement all the necessary movements of control organ and casting box are obtained without the parts coming out 20 of engagement with each other.

In the drawing representing my invention by way of example Fig. 1 is a vertical section through the driving gear, and Fig. 2 a horizontal section through same.

25 Fig. 3 is a sectional view of the casting machine taken substantially on line A—B of Fig. 5.

Fig. 4 is a section taken substantially on line C—D of Fig. 5.

30 Fig. 5 is an end elevational view.

By means of a coupling 1, 2 the shaft 3 is coupled with a suitable motor. On the shaft 3 is fixed a worm 4 which drives the worm-wheel 5, which, together with the spur-wheel 6 and one-toothed wheel 7, is loosely mounted on the shaft 8. The spur-wheel 6 engages in a toothed segment 9 fixed on the shaft 10 and adapted to turn the segments 11, 12, 13 and 14. The larger segment 11 in

40 certain positions engages the spur-wheel 15, and the smaller toothed segment 12, in certain other positions, engages the spur-wheel 16. The spur-wheels 15 and 16 are fastened on the shaft 17, which, by a partial rotation, 45 closes the box and moves the closed box towards the outlet of the pot and also moves the box away from the pot and opens same. The toothed segment 14 has two oppositely situated series of teeth, which, in certain angular positions, engage in the same spur-wheel 18 fastened on the shaft 8. This shaft serves, in a well known manner, to open and close the connection between the melting pot and the casting box. In the angular 55 positions in which the spur-wheel 6 stands

opposite the non-toothed part of the segment 9, the toothed segment 13 is turned tooth by tooth by the one-toothed wheel 7, the toothed segments 9, 11, 12 and 14 being turned at the same time. The shaft 10 serves therefore as timing shaft. Between each turning movement of the toothed segment 13, this segment is held in position by a pawl 27, one end of which engages in the teeth of the segment 13, while the opposite end bears against the circumference of the one-toothed wheel 7 in which a properly situated recess permits the pawl to spring over a tooth when the segment 13 is being moved.

In order to assure that the shaft 8, by 70 which the controlling organ for the molten metal is operated, after the drive of the gear by the toothed segment 14 and spur-wheel 18 has stopped, is kept in the proper position, a Geneva stop 19 is provided which 75 operates in such a way in conjunction with a disc 20 on the shaft 10 that the shaft 8 is prevented from turning by the circumference of the disc 20, until, by the operation of the one-toothed wheel 7 and segment 13, 80 toothed parts of the segment 14 again come into engagement with the spur-wheel 18, in which position recesses 21 and 22 of the disc 20 permit the stop-disc 19 to turn.

A similar stop-disc is fastened on the shaft 85 17, which, as soon as the casting box is closed and pressed against the outlet of the pot, is prevented from turning further by a disc 24 on the shaft 10. This disc 24 has also cut out portions 25, 26 which enable the disc 23 and 90 shaft 17 to turn further, when toothed parts of the toothed segments 11 and 12 again come into engagement with the spur-wheels 15, 16.

In the drawing Figs. 3, 4 and 5 the melting pot is indicated by reference character 95 *a*; in the bottom of this pot is the means for opening and closing the outlet *c* of the pot, which in this instance consists of a long valve *b* which is opened and closed by the arm *d* on the end of the valve, and connecting rod *e* which is attached at one end to said arm *d* and at its other end to a similar arm *f* mounted on the shaft 8.

The casting box consists as usual of a core 105 *g* and a bed *h*; in order to open and close this casting box the bed *h* is lowered and raised by the cranks *i* which through the agency of the connecting rods *k* move the bed *h* in the guiding frame *l*; for the pur- 110

pose of pressing the casting box against the outlet *c* of the pot *a* the frame *l* is pivoted at *m* to a fixed frame and is seated on cranks *n* which have just sufficient eccentricity to raise the frame *l*, the short distance necessary to press the casting box against the pot opening; the cranks *i* and *n* being rotated by shaft 17.

The operation of the gear is as follows:—

10. By the shaft 17 the casting box, which, at the beginning, is open and moved away from the outlet of the pot, is first closed and moved towards the pot outlet, then kept in this position until the plate is cast and 15 cooled, whereupon, by a further turning motion of the shaft 17, it is moved away from the pot outlet, then opened.

The part turn of the shaft 17, necessary for closing the box and moving it towards the pot opening, is obtained by the rotating 20 spur-wheel 6 which engages in the toothed part of the toothed segment 9. The turning movement of the toothed segment 9 is transmitted by the segment 11—whose 25 toothed part engages, at this moment, in the spur-wheel 15—to this wheel 15 and the shaft 17. The length of the toothed part of the segment 11 is so calculated that when the spur-wheel 15 arrives just opposite the non-toothed part of the toothed segment 11, the shaft 17 has made a half turn. The radius 30 of the segment 11 and spur-wheel 15 are so calculated that the half turn of the shaft 17, and, consequently, the closing of the box, 35 and its movement towards the pot outlet, take place quickly. The concave part of the disc 23 is then directed towards the circumference of the disc 24 and cannot therefore turn further, so that the casting box will 40 be secured in position.

At this moment, or somewhat before, the toothed part of the segment 14 will come into engagement with the spur-wheel 18, so that this wheel and the shaft 8 will be turned by the worm-wheel 5 through the agency of the 45 spur-wheel 6, segment 9, shaft 10 and segment 14. By this turning of the shaft 8 the controlling organ for the molten metal is opened and the casting box filled. Until 50 the contents of the box have solidified this connection between the molten metal in the pot and the cast plate should be maintained, and this is obtained by the fact that after the partial turn of the shaft 8 the spur-wheel 55 6 will arrive opposite the non-toothed part of the segment 9. At the same time however the toothed part of the segment 13 is brought within reach of the one-toothed wheel 7, so that for each further rotation of the worm 60 wheel 5 the segment 13 will be advanced one tooth. Consequently, the shaft 10 with all parts on same will turn slowly until the toothed part of the segment 9 again comes into engagement with the spur-wheel 6, 65 whereupon the shaft 10 will again be turned

for driving operations. Firstly, the second series of teeth on the segment 14 will turn the spur-wheel 18 and shaft 8, in order to close the connection between the pot and box. Then, by the toothed segment 12, spur-wheel 70 16 and shaft 17, the casting box will be moved away from the pot and opened. As the spur-wheel 16 is larger in diameter than the spur-wheel 15, the opening of the box will take place slower than the closing, thus 75 preventing the matrix from being injured during its stripping from the cast plate. At this moment, the spur-wheel 6 will be opposite the middle part of the teeth on the segment 9, and, by an automatic device of any known construction, the shaft 3 will be uncoupled from the motor. All parts will then be in the proper position for repeating the whole operation when the motor is again 80 coupled to the shaft 3.

What I claim and desire to secure by Letters Patent of the United States is:

1. An automatic machine for casting stereo-plates, comprising in combination, a melting pot with outlet, an organ to open and close said outlet, a casting box adapted to be opened and closed and to be pressed in the closed condition against the outlet of said pot, a continuously rotating part, a timing shaft through the agency of which the organ to open and close the outlet of said pot and the casting box are operated, mechanical elements by which said continuously rotating part turns said time shaft quickly in the operating periods of said organ and said casting box, and slowly in the non-operating periods, substantially as, and for the purpose, set forth.

2. An automatic machine for casting stereo-plates, comprising in combination, a 105 pot containing molten metal and having an outlet, an organ to control the flow of metal through said outlet, a casting box adapted to be opened and closed and to be pressed in the closed condition against the outlet of said pot, and a gear adapted to close, and press, said box against the opening of said pot more quickly than to open said box, substantially as, and for the purpose, set forth.

3. An automatic machine for casting 115 stereo-plates, comprising in combination, a pot containing molten metal and having an outlet, an organ to control the flow of metal through said outlet, a casting box adapted to be opened and closed, a continuously rotating part, a shaft in driving connection with said box, and a timing shaft adapted to connect said continuously rotating part with said shaft in different gear ratios and in prescribed intervals, substantially as, and 120 for the purpose, set forth.

In testimony whereof I have signed my name to this specification.

ERNST MÜLLER.
